UNITED STATES PATENT OFFICE.

JACOB A. ULMAN, OF BALTIMORE, MARYLAND, ASSIGNOR, BY MESNE ASSIGNMENTS, TO THE ANGLO-AMERICAN PATENT BOTTLE COMPANY LIMITED, OF LONDON, ENGLAND.

NON-REFILLABLE BOTTLE.

1,111,046.

Specification of Letters Patent. Patented Sept. 22, 1914.

Application filed November 30, 1910. Serial No. 594,945.

To all whom it may concern:

Be it known that I, JACOB A. ULMAN, a citizen of the United States, residing at Baltimore city, State of Maryland, have invented certain new and useful Improvements in Non-Refillable Bottles, fully described and represented in the following specification and the accompanying drawings, forming a part of the same.

This invention relates to improvements in non-refillable bottles; it being the object of the present invention to provide a bottle of this class in which will be overcome a certain difficulty in pouring which develops under certain conditions with certain liquids; this particular difficulty being the liability of the valve, notwithstanding the tilting of the bottle to pouring position, to remain seated and thus prevent the pouring of the contents of the bottle.

As a full understanding of the improvements of the present invention can best be had from a detailed description of an organization embodying the same, such description will now be given in connection with the accompanying drawings, in which—

Figure 1 is a vertical elevation of a bottle equipped with the present invention. Fig. 2 is a vertical section of the same. Fig. 3 is a view similar to Fig. 2, with the bottle tilted to pouring position. Figs. 4, 5, 6 and 7 are sections on the lines 4, 5, 6, 7 respectively, of Fig. 2; and Fig. 8 is a side elevation of part of the bottle neck.

The bottle here illustrated is that shown and described in the application of Maurice Switzer and Joseph D. Lacroix, filed November 7, 1910, Serial No. 591,054 except for the addition thereto of one feature constituting the present invention and which will be hereinafter fully described. The following brief general description of the other features of the bottle will, therefore, be sufficient.

Referring to said drawings, *a* represents the bottle body, terminating at its upper end in a neck portion *b*, to which is permanently secured by cement and otherwise a neck containing the valve and valve-controlling mechanism by which the bottle is rendered non-refillable. The neck is, in the process of manufacture, made up of two parts *c* and *d* of porcelain, which, however, are so united by an outer film *e* of enamel and the inter-

locking engagement of their abutting and correspondingly shouldered edges as to become, in effect, a unit or integral, as described in said application of Switzer and Lacroix. The part *c* contains a valve seat *f*, 60 of porcelain, chamfered at its lower outer edge to fit a correspondingly shaped shoulder provided by the inner upper edge of the neck portion *b* of the bottle body *a*, and at its upper edge fitting into a recess *g* in the lower end of part *c*; a hollow inverted cup-shaped valve *h*, preferably of porcelain, resting on this valve seat; an approximately pear-shaped valve-seating weight *i*, of glass or porcelain, resting sidewise on the upper 70 end of the valve *h*; and a baffle *j* which, among other things, limits the movement of weight *i*; integral vertical ribs *k* being also formed in the neck part *c* for guiding valve *h* in its vertical or opening and closing movements. Baffle *j*, which is integral with the neck part *d*, closes the bottle neck except for a passage between it and the inner surface of the latter, into which, however, project two horizontal rows of alternating or staggered projections *l*, *m*, which will permit the passage of the liquid contents of the bottle but will prevent the insertion of a wire or the like sufficiently far into the bottle neck to tamper with the valve *h* or weight *i*. At 85 the ends of each projection *l*, *m* are vertical ribs *n*, which it is obvious will engage the end of any wire or the like inserted in the bottle neck and prevent further downward movement thereof. The insertion of a wire 90 or the like is still further guarded against by the provision of shoulders *o* in the neck-portion *c* projecting inwardly beneath the projections *l*, *m*, so that a wire cannot be passed between the outer ends of said projections and the inner surface of the neck into the lower end of part *c* containing the valve *h*. Baffle *j* is also provided at its lower end with a recess *p* for the accommodation of weight *i*, this recess and the weight 100 *i*, valve *h*, and seat *f* being of such size and so arranged relatively to each other as to provide for free rocking movement of said weight, and also a limited movement thereof, and of valve *h* longitudinally of the bottle neck.

While the bottle is in an erect position, the valve *h* and weight *i* will occupy the positions in which they are shown in Fig. 2, with the valve *h* held to its seat by its own weight 110

and that of weight i . When, however, the bottle is tilted to pour out some of its contents, and passes from a horizontal portion to the partially inverted position shown in 5 Fig. 3, the valve, relieved of the weight of weight i , which has moved into recess p , and aided by the pressure of the liquid in the bottle, will be unseated and assume the position in which it is shown in Fig. 4. On 10 turning the bottle upwardly, as soon as it passes a horizontal position, and approaches an erect position, weight i , rocking in recess p and moving downwardly at right angles to the bottle neck, will, as the liquid recedes from the bottle neck, force valve h to its seat, aided, of course, by the weight of the valve itself.

The bottle neck, made in two parts c , d , united as described in said application of 20 Switzer and Lacroix, is secured to the bottle body a by a collar r of suitable metal inclosing the upper end of the neck portion b of the bottle body and the lower portion of the neck member c , both of which portions are 25 provided with circumferential indentations or recesses, into which the metal of collar r is forced or spun by a suitable tool. To prevent leakage, a gasket s , of suitable material is interposed between the abutting edges of 30 the neck portion b and neck member c . At the base of the recess p in baffle plate or plug j are provided projections t which prevent adhesion of the weight i to the bottom of the recess.

35 The valve mechanism of the bottle operates satisfactorily and will except that, under certain low thermal conditions if the contents of the bottle be alcoholic, it has been found that the valve at times adheres so tenaciously to its seat (with which it must, of course, make perfect contact to prevent refilling) that it is almost impossible to unseat it and to therefore pour the contents of the bottle. I have discovered that this is 40 due to the production of a partial vacuum in the bottle below the valve and its seat, and I have also discovered that the formation of this vacuum, and, therefore, the adhesion of the valve to its seat, may be avoided by a 45 contracted air passage u through which in the closed position of the valve the bottle neck above the valve seat communicates with the body of the bottle. Such air passage is, in the particular valve mechanism shown 50 and described herein, preferably formed in the upper end of the valve h , because it has been found that in this position it is less liable to permit the passage of liquid downward through it than it might be in other 55 positions, particularly as the weight i in its closed position rests immediately on and partially closes it. By "contracted air pas-

sage", as that phrase is here used, I mean a passage large enough to permit the passage of air from one side of the valve or valve 65 seat to the other, but small enough to prevent, on account of the air pressure inside the bottle, the passage of any substantial amount of liquid from the neck of the bottle into the body thereof.

70 What is claimed is:—

1. In a non-refillable bottle the combination of a valve and seat therefor interposed between the bottle body and neck, a weight resting upon and having a curved surface 75 in contact with the upper end of said valve, and a contracted air passage through said valve in line with said weight and arranged to be closed thereby, said passage connecting the body and neck in the closed position of 80 the valve.

2. In a non-refillable bottle the combination of a valve and seat therefor interposed between the bottle body and neck, a pear shaped weight resting upon the upper end 85 of said valve, and a contracted air passage through said valve, in line with said weight and arranged to be closed thereby, said passage connecting the body and neck in the closed position of the valve.

90 3. In a non-refillable bottle the combination of an inverted cup-shaped valve and seat therefor interposed between the bottle body and neck, a pear-shaped weight resting on the upper end of said valve, and a contracted air passage through said valve in line with said weight and arranged to be closed thereby, said passage connecting the body and neck in the closed position of the valve.

95 4. The combination, in the neck of a bottle, of a valve-seat having a central opening in line with the neck-opening, an inverted cup-shaped valve normally resting at its lower edge on said seat and closing the opening therein and adapted to tilt upon and then move bodily away from said seat when the bottle is tilted to pouring position, said valve having a contracted air passage, a weight normally resting upon the upper end 100 of the valve and controlling its movements, said weight being in line with the air passage and having a curved surface in contact with the valve, and means above the weight for limiting the movements thereof, substan- 105 tially as described.

110 In testimony whereof, I have hereunto set my hand, in the presence of two subscribing witnesses.

JACOB A. ULMAN.
